UNITED STATES PATENT OFFICE.

SAMUEL E. STOKES, OF PHILADELPHIA, PENNSYLVANIA.

ELEVATOR.

SPECIFICATION forming part of Letters Patent No. 469,984, dated March 1, 1892.

Application filed September 24, 1885. Serial No. 178,006. (No model.)

To all whom it may concern:

Be it known that I, SAMUEL E. STOKES, a citizen of the United States, residing in Philadelphia, Pennsylvania, have invented certain 5 Improvements in Elevators, of which the following is a specification.

My invention consists of certain improvements in devices for controlling the movements of elevator-cars, as fully described hereinafter.

In the accompanying drawings, Figure 1 is a diagram of an elevator car and shaft illustrating my improvements applied thereto. Fig. 2 is a similar view illustrating my invention in its simplest form. Fig. 3 is a sectional plan view on the line 1 2, Fig. 2, on an enlarged scale. Figs. 4, 5, and 6 are views of modified forms of devices for operating the valve-ropes, and Figs. 7 and 8 show modifications of power-operating devices for the car.

In the drawings I have shown the device attached to a hydraulic elevator such as is used for passenger travel; but I have deemed it best for the sake of clearness to omit the 25 hoisting-ropes and guides.

A represents the ordinary elevator-car, and B the different floors of a building.

C is a tension device to which are attached the upper ends of the power-controlling ropes, 30 and D is a valve-chest carrying a weighted lever e, to which are connected the lower ends of said ropes. It will be understood that the valve is usually placed in the basement or on the lower floor of the building near the lower 35 end of the elevator-shaft, and in the present instance it is what is termed a "three-way valve," which is open when the valve-lever e is in the position shown in Fig. 1 and the elevator-car is ascending. When, however, the

40 lever e assumes the position shown by dotted lines, the valve is open to the exhaust and the car descends. Connected by a link e' to the piston-rod d of the valve is a pivoted lever e, the opposite end of which is provided with an 45 adjustable balance-weight d², the lever being fulcrumed on a rock-shaft e² on the valve-easing. The lower end of the rope a is secured to said valve-lever e, and its upper end, after 50 passing around the pulleys on the car, as hereinafter described, is secured to the yielding

support or bar F, which slides in suitable bearings f', secured to one side of the elevator-shaft. This bar F is attached by a link to a lever E, pivoted to one side of the elevator-shaft and weighted sufficiently to keep the 55 tension always on the rope, so that the valve may be accurately operated. This tension device is not at all times absolutely essential to the proper operation of the various modifications of my invention, as it will be understood that in some instances the strain caused by the opening and closing of the valve is insufficient to overcome the weight on the counterbalance-lever, so that practically, so far as the operation of the valve is concerned, the 60 end of the rope may be said to be connected to a fixed point.

Adapted to a suitable bearing g in the side of the car is a shaft H, having an arm h, carrying a spindle i, on which revolves loosely 70 a rope wheel or pulley I. The outer end of the spindle is adapted to an arm j of a two-armed lever J, which has a stud k on the arm j² for a purpose described hereinafter. The lever J is pivoted to a bar G at k', which is 75 directly in line with the shaft H and in fact constitutes a continuation of the shaft. Some distance below the shaft H is a shaft or stud L, adapted to bearings in the side of the car A, and on which is mounted a loose pulley M, 80 the rope being attached to the tension device at the top of the well and extending down around the pulley M, up over the pulley I, and down to the valve-lever e, as shown in Fig. 2.

The shaft H can be provided with a suitable operating-lever, as shown, Figs. 1 and 2, by dotted lines, or with any of the operating devices shown in Figs. 4, 5, and 6, and hereinafter described.

The above description alludes solely to an 90 elevator-controlling device in which but a single rope is employed, as shown in Fig. 2 of the drawings, and I will now describe my invention in connection with a valve-operating device employing two ropes, this special construction, however, being claimed in Letters Patent of the United States granted to me on the 5th day of June, A. D. 1888, No. 384,096. The tension devices and valve are the same 95 as those used in the construction illustrated 100

in Fig. 2, with the exception that the lever *e* of the valve, instead of being a single-armed lever, is a double-armed lever, and the bar *F* of the tension device is provided with two arms *f*, to which the two ropes *a* *a'* are connected, as fully shown in the drawings. The arm *J* is in this construction provided with three small arms, one of which is provided with a stud *k*, which comes in contact with the shifting cam *P* *P'*, described in connection with the single-rope mechanism. When the handle *N* (shown by dotted lines) is in the upper position *x*, the elevator is stationary, and when thrown over to the position *y* the car ¹⁵ will be elevated, while when the handle is thrown to the position *z* the car will descend. Near the top and bottom of the elevator-shaft *I* place cam-blocks *P* *P'*, each provided with two abrupt cam-faces and one less abrupt, so ²⁰ that as the car nears the limit of its movement the valve will be shut off about half-way, gradually shut off about a quarter, and finally shut off entirely, which operation will let the car come to a gradual stop, preventing ²⁵ sudden jar.

Various devices may be employed to operate the movable rope-pulley in place of the lever shown in Figs. 1 and 2, instances of a number of such modifications being illustrated in Figs. 4, 5, and 6.

In Fig. 4 I have shown the lever *N* geared to the shaft *H* through elliptical spur-gears *H'*, which when the handle is moved in either direction will commence first to operate the ³⁵ valve slowly, then increase the speed as the handle is turned, so as to insure the more gradual starting and stopping of the car.

In Fig. 5 I have shown the lever *N*, provided with a segment *m*, gearing with a pinion *n* on the shaft *H* in the relation of two to one, such gearing being particularly applicable where only a limited movement of such lever can be obtained.

In Fig. 6 I have shown the shaft *H*, geared ⁴⁵ to supplementary shaft *S* by a pinion, and internal segmental rack *S*, carried by the shaft *H*. This shaft *S* is provided with a hand-wheel *t*, which when turned in one direction or the other will operate the valve to raise or ⁵⁰ lower the car. To the outer end of the shaft *H*, I prefer to attach a pointer *s*, moving over a dial-plate marked "Hoist," "Stop," "Lower." When the wheel is turned, the pointer *s* will move and indicate to the operator which way ⁵⁵ the valve is moved. This arrangement is especially adapted for use in private houses and buildings where the elevator is not operated by a regular attendant.

It will be understood that my improvements ⁶⁰ may be applied to other constructions of elevators than those operated by hydraulic power. For instance, in Fig. 7 I have shown the lower end of the rope *a* attached to one arm *t'* of a bell-crank lever *S*, the opposite

end of the said lever being in the form of a ⁶⁵ belt-shifting finger *t*, adapted to control the position of a driving-pulley *u* and to move said belt onto raising-pulleys *v* *v'* or an intermediate loose pulley *v*².

A further modification is illustrated in Fig. ⁷⁰ 8, in which the bell-crank lever *S* has an arm *t'*, in the form of a clutch-lever, adapted to operate a clutch *V*, intermediate between winding and lowering drums *V* *V'*, on which are wound the hoisting-ropes attached to the ⁷⁵ elevator-car.

Having thus described my invention, I claim and desire to secure by Letters Patent—

1. The combination of a rope attached to a fixture at one end and a power-controlling ⁸⁰ device to which the other end of the rope is connected, with a rope-pulley *M* and wheel or pulley *I*, attached to a car, a lever provided with a pin or lug controlling the position of the wheel or pulley *I*, and cam-blocks *P* *P'* ⁸⁵ to act on said pin or lug to automatically stop the car, substantially as described.

2. The combination, in controlling devices for elevators, of a suspended cable connected to the stopping and starting device, a car having devices for acting upon, and moving said cable, and contact-plates at the upper and lower limits of travel of the car to engage said devices on the car and automatically stop said car.

3. The combination of a rope hung within an elevator-well, with a tension device connected to the upper end of said rope, a power-controlling device to which the lower end of said rope is attached, an elevator-car, pulleys ¹⁰⁰ thereon over which the rope passes, and an adjustable bearing for one of said pulleys, whereby the distance between the pulleys may be increased or diminished, substantially as described.

4. The combination of a rope within the elevator-well and hung from a fixture at the top of said well, and a positive power-controlling device to which the lower end of said rope is connected, with an elevator-car, a stationary rope-pulley and a movable rope-pulley, both situated on the exterior of the said car, a shaft extending into the car, and devices on the inner end of said shaft for adjusting the movable rope-pulley toward and ¹¹⁵ from the stationary rope-pulley, substantially as described.

5. The combination of an elevator-car, a cable, a support therefor at the top of the elevator-well, a valve connected to said cable ¹²⁰ for controlling the movement of the elevator, and a weight counterbalancing said support and cable, substantially as described.

6. The combination of the elevator-car, a weighted lever, a valve for controlling the movement of the car, and a cable connected at its upper end to the weighted lever and at its lower end to the valve, with mechanism on

the car engaging with the cable and by which the valve is operated from the car, substantially as and for the purpose set forth.

7. The combination, in a valve-controlling device for elevators, of a valve mechanism for controlling the operating of the elevator-car, a stationary valve-operating rope connected at one end to the valve mechanism, and a yielding support to which the opposite end of the rope is attached, with mechanism on

the car engaging with said rope to actuate the valve mechanism, substantially as specified.

In testimony whereof I have signed my name to this specification in the presence of two subscribing witnesses.

SAMUEL E. STOKES.
